[57] **CLAIM**

The ornamental design for an universal frame for supporting duffle bags, as shown and described.

DESCRIPTION

FIG. 1 is a front, top and side perspective view of the frame for supporting duffle bags showing my new design;
FIG. 2 is a front elevational view thereof, the rear, top and bottom being mirror images of the front shown in FIG. 2;
and,

FIG. 3 is an end elevational view thereof, the end opposite being a mirror image of the end shown in FIG. 3.

1 Claim, 2 Drawing Sheets

FIG. 1.

FIG. 3.

FIG. 2.
